UNITED STATES PATENT OFFICE.

PHILIP TELL DODGE, OF NEW YORK, N. Y., ASSIGNOR TO MERGENTHALER LINOTYPE COMPANY, A CORPORATION OF NEW YORK.

MEANS FOR THE PRODUCTION OF PRINTING-SLUGS.

1,084,617.

Specification of Letters Patent.

Patented Jan. 20, 1914.

Original application filed July 15, 1907, Serial No. 383,831. Divided and this application filed September 30, 1912. Serial No. 723,050.

To all whom it may concern:

Be it known that I, PHILIP TELL DODGE, a citizen of the United States residing at New York, in the county of New York and State of New York, have invented certain new and useful Improvements in Means for the Production of Printing-Slugs, of which the following is a specification, reference being had therein to the accompanying drawing, being 10 a division of original application filed July 15, 1907, Serial No. 383,831.

For various special purposes, such as the printing of addresses on newspapers, it is desirable to have white characters appear on 15 a black background.

The object of my invention is to secure the production of forms for this purpose in composing machines, such for example as the Mergenthaler linotype. To this end I 20 provide dies having a mercantile form similar to those of the linotype, but having instead of the intaglio characters, cameo characters so formed and arranged as to enter the face of the mold and form intaglio characters therein. These dies may be used in a 25 linotype machine of ordinary construction, and composed in lines, the justified lines presented to the mold, and thereafter distributed in the same manner that the ordinary 30 matrices are distributed in such machines, as illustrated for example in Letters Patent of the United States No. 436,532. A series of slugs formed on my plan and assembled side by side, as they will be in the machine, will present a solid flat printing surface with intaglio characters therein. The 35 surface of the form, upon being inked and pressed upon the paper, will produce thereon a solid black background with white letters therein.

Referring to the drawings: Figure 1 is a perspective view showing a series of slugs produced in accordance with my invention. Fig. 2 is a perspective view of one of the 45 dies used in the machine for producing these slugs. Fig. 3 is a cross-section of the mold with one of the dies of the line presented thereto, showing the manner in which the character on the die enters the face of the 50 mold so as to be covered and surrounded by the type metal.

The dies B consist each of a flat metallic plate having on one edge in relief a character or die b. The dies B are preferably

made of the same marginal form as the ordinary matrices used in linotype machines, and are provided with distributing teeth b' in the upper end, and otherwise adapted to be used in the Linotype machine in precisely the same manner that the ordinary matrices 55 are used. The mold C, with which the dies coöperate, is provided with a slot or mold proper c of the exact dimensions of the required slugs. This mold may be used and arranged in the machine in the same manner that the ordinary mold is used, to receive molten type metal to form slugs 60 therein. The dies have their characters b made of such size and so located as to project into the front of the mold slot. The 65 line of dies B, assembled side by side and presented tightly against the face of the mold, completely closes the same and prevents the escape of molten metal. The metal, on entering the mold, will flow over 70 and around the characters b and against the face of the matrices, and the resultant slugs A have the appearance shown in Fig. 1, with flat upper edges and the series of characters therein. These slugs are made of 75 uniform height, preferably type-high, and of any required length or measure. They are adapted to fit tightly together side by side, and each slug contains in its upper or printing edge the intaglio characters a in 80 the order and arrangement in which they are to appear in print. The slugs are so formed that when assembled side by side, their upper edges will present a continuous 85 unbroken surface adapted to print on the 90 paper a black background without lines or breaks between the lines of characters.

While in the accompanying drawings and foregoing description I have set forth my invention in the form I prefer to adopt, it 95 will be understood that the same may be modified or changed within the skill of the mechanic without departing from the limits of the invention; and it will be further understood that the invention is not 100 limited to any particular form or construction of the parts except in so far as such limitations are specified in the claims.

It will be observed that the printing slug with the intaglio characters therein is 105 formed in the mold directly by the injection of the molten metal against and around the cameo characters on the dies and against

the plane surfaces immediately surrounding the characters, these plane surfaces being specially and designedly formed so that they will give to the cast slug, corresponding and uniform plane surfaces of a character suitable to take the ink and transfer it to the paper, and in this way produce a black background. In order, by the operations described, to produce printing slugs which may be employed for printing directly therefrom a black background around white characters, the intaglio characters therein must read from right to left, and the dies assembled before the mold must consequently read from left to right, otherwise the printing bar cast directly from the dies would print characters on the paper reading the wrong way. Moreover, by reason of the fact that the plane surface of each matrix is uniform and smooth, it presents an impression-producing surface which not only encompasses the intaglio character but one which is coextensive (or practically so) with the dimensions of the mold slot which it closes. As a result, the printing surface of the slug produced by a series of matrices thus formed will be coextensive with the dimensions of the mold slot, or practically so. By the expression "encompassing" in describing the extent of the impression-producing surface is not necessarily meant a surface which entirely surrounds the intaglio character, for in certain cases the character may extend up to one or more of the edges of the impression-producing surface, without departing from the limits of the invention.

Having described my invention, what I claim and desire to secure by Letters Patent is:—

40 1. In a mechanism for producing print-

ing slugs adapted to produce a black background around white characters, the combination of a slotted mold and a series of dies adapted to close the mold and each provided with a cameo character extending into the mold and arranged to read from left to right and having an impression-producing surface encompassing said cameo character and substantially coextensive with the dimensions of the die-closing portions of the mold slot; whereby printing elements formed by the injection of metal into the mold will have flat printing surfaces which encompass intaglio characters reading from right to left.

2. In combination with a slotted mold, dies provided with cameo characters and with encompassing plane impression-producing surfaces, said dies adapted to be assembled in a line and presented to the mold, with the characters projecting into the mold slot and reading from left to right and with the plane surfaces closing the front of the mold slot to effect an impression-producing surface practically coextensive with the dimensions of the mold slot; whereby by the supply of molten metal to the mold, a printing slug will be produced therein directly from the dies, which slug will have intaglio characters reading from right to left and encompassed by printing surfaces to produce a black background around white characters.

In testimony whereof I affix my signature in presence of two witnesses.

PHILIP TELL DODGE.
